ELECTRONIC TEACHER CONSOLE

Chester J. Barecki, Grand Rapids, and Carl W. Sundberg and Montgomery Ferar, Southfield, Mich., assignors to American Seating Company, Grand Rapids, Mich., a corporation of Delaware

Filed Jan. 12, 1967, Ser. No. 5,397

Term of patent 14 years

(Cl. D33—7)

The side of the desk not shown is a mirror image of the side shown.

We claim:

The ornamental design for an electronic teacher console, as shown and described.
